QUADDING APPARATUS

Loran O. Rhodes, Craig, Colo.

Application May 14, 1948, Serial No. 27,015

2 Claims. (Cl. 199—51)

1

This invention relates to improvements in quadding apparatus for typographical machines, the primary object of the invention being to provide simplified, less expensive apparatus of this kind.

Another important object of the invention is to provide quadding apparatus of the above indicated character which can be readily applied to typographical machines not already equipped with quadding apparatus.

Other important objects and advantageous features of the invention will be apparent from the following description and accompanying drawings, wherein, for present purposes of illustration only, a specific embodiment of the invention is set forth in detail.

In the drawings:

Figure 1 is a rear elevation showing the improved quadding apparatus associated with related components of a conventional typographical machine, and

Figure 2 is a transverse vertical section taken on the line 2—2 of Figure 1.

Referring in detail to the drawings, the numeral 5 generally designates the justification block of a conventional typographical machine, above and at opposite ends of which are positioned jaws 6 and 7, respectively, supported by conventional means (not shown) for movement toward each other by locking shafts or rods 8 and 8', respectively, which abut the outer ends of the jaws in a conventional manner. In machines having automatic quadding apparatus, mechanical means connected to the shafts 8 and 8' and coordinated with the vertical movement of the justification block 5, are provided for operating the jaws 6 and 7, which mechanical means are complicated, and expensive both to construct and to repair. In accordance with the present invention such mechanical means are eliminated, and their functions replaced by simple toggle linkages 10, 10'. The jaw 7 is substantially shorter than the jaw 6, and is provided with an extension 7', lengthening the center portion thereof in order to block metal flow when the jaw 7 is fully extended toward its companion jaw 6, and making the jaw 7 in effect the same length as the jaw 6.

The similar linkages 10 each comprises a pair of equal length links 11, 11' pivoted together at their lower ends on a horizontal pin 12. The upper end of the inner link 11 is pivoted at 14 to the lower end of a bracket arm 15 secured at its upper end, as indicated at 16, to the back of the related one of the jaws 6 and 7, at points near

2

the laterally inward ends of the jaws. The pins 12 can be moved longitudinally to bring their heads 13 into and out of position, as indicated in Figure 2, for engagement by the justification block 5 as it rises. Therefore, when rod or pin 12 controlling jaw 7 is pushed rearwardly by the operator, into the dotted line position shown in Figure 2, and the rod 12 associated with the jaw 6 is left in the full line position shown in Figure 2 so as not to be engaged by the block 5, the linkage 10 of the jaw 7 will be elevated and jaw 7 will be moved inwardly when block 5 rises, and jaw 6 will remain stationary. This will produce a line flush to the left. By reversing the positions of the two control rods 12, 12 a line flush to the right will result. When both rods 12, 12 are pushed in, a centered line is produced.

With reference to the jaw 6 the upper end of the laterally outward link 11' of its linkage 10 is pivoted at 17 to the laterally inward end of a horizontal arm 18 having a collar or abutment 19 on its laterally outward end, which is clamped on the rod or shaft 8 of the jaw 6. A helical spring 20 is stretched between the upper ends of the links 11, 11', the parts being so proportioned and arranged that in the depressed position of the justification block 5 the links 11, 11' are held by the spring 20 in acutely angulated relation with very little tension on the spring, whereas in the elevated position of the justification block 5 the links 11, 11' are spread away from each other, and move the jaws 6, 7 toward each other as shown in dotted lines in Figure 1. The spring 20 is thereby considerably stretched so that the spring 20 is tensioned sufficiently to return the jaws 6, 7 to starting position when the justification block 5 returns to the depressed position, shown in full lines in Figure 1. With reference to the jaw 7, a horizontal rod 18' has on its outward end a collar or abutment 19' which is clamped on the rod 8' associated with the jaw 7, the inward end of the rod 18' being pivoted at 17' to the upper end of the outer link 11' of the associated linkage 10.

With variations which will occur to persons skilled in the pertinent art, the above described arrangement of quadding apparatus can be installed and operated in machines not already equipped with quadding apparatus.

It is apparent from the foregoing that upon rise of the justification block 5 from its depressed, full line position in Figure 1, to the dotted line position, the jaws 6 and 7 will be moved toward each other the required amount to clamp there-

between the line of matrices 21, with or without spacebands.

What is claimed is:

1. In a typographical machine having a pair of jaws supported for horizontal movement toward each other to clamp a line of matrices therebetween and for horizontal movement away from each other to release such line of matrices and relatively stationary abutments at the outer ends of and limiting movement of said jaws away from each other, and a justification block below said jaws and adapted to be moved upwardly beneath said jaws from a depressed position to produce justification of a line of matrices clamped between said jaws; the improvement which comprises for each of said jaws a rod secured to the associated abutment and extending alongside of the jaw, a linkage comprising an outer vertical link pivoted to depend from the inward end of said rod, an inner vertical link pivoted to depend from the jaw, pivot means pivoting the lower ends of the outer and inner links together, said pivot means comprising a rod having a portion positioned in the path of movement of said justification block and arranged to be engaged and elevated by the justification block as it rises whereby said inner and outer links are spread so as to move the associated jaw toward the other jaw, and spring means connected to said inner and outer links for contracting said inner and outer links toward each other as the justification block subsides toward the depressed position and thereby moving the associated jaw outwardly away from the other jaw and into engagement with the related abutment.

2. In a typographical machine having a pair of jaws supported for horizontal movement toward each other to clamp a line of matrices therebetween and for horizontal movement away from each other to release such line of matrices and relatively stationary abutments at the outer ends of and limiting movement of said jaws away from each other, and a justification block below

said jaws and adapted to be moved upwardly beneath said jaws from a depressed position to produce justification of a line of matrices clamped between said jaws; the improvement which comprises for each of said jaws a rod secured to the associated abutment and extending alongside of the jaw, a linkage comprising an outer vertical link pivoted to depend from the inward end of said rod, an inner vertical link pivoted to depend from the jaw, pivot means pivoting the lower ends of the outer and inner links together, said pivot means comprising a rod having a portion positioned in the path of movement of said justification block and arranged to be engaged and elevated by the justification block as it rises whereby said inner and outer links are spread so as to move the associated jaw toward the other jaw, and spring means connected to said inner and outer links for contracting said inner and outer links toward each other as the justification block subsides toward its depressed position and thereby moving the associated jaw outwardly away from the other jaw and into engagement with the related abutment, the rod of each of said pivot means being longitudinally adjustable to selectively retract the justification block engaging portion thereof to positions in which either of the rods fails to be operatively engaged by the justification block and the associated jaw remains stationary while the remaining jaw is moved inward and outwardly as the justification block rises and subsides.
